BIRD HOUSE

Olga O. Bewley, Rte. 1, Box 148, Ojai, Calif.

Filed June 15, 1961, Ser. No. 65,629

Term of patent 14 years

(Cl. D31—2)

FIG.1.

FIG.2.

FIG.3.

The left side of the bird house is similar in appearance to FIGURE 3 except that the left opening is slightly lower as evident from FIGURE 1.

I claim:

The ornamental design for a bird house, substantially as shown and described.
